UNITED STATES PATENT OFFICE

171,434

DRINK STIRRER OR SIMILAR ARTICLE

Robert R. Borgfeldt, Chicago, Ill.

Application January 7, 1953, Serial No. 23,065

Term of patent 14 years

(Cl. D44—1)

To all whom it may concern:

Be it known that I, Robert R. Borgfeldt, a citizen of the United States, residing at Chicago, in the county of Cook and State of Illinois, have invented a new, original, and ornamental Design for a Drink Stirrer or Similar Article, of which the following is a specification, reference being had to the accompanying drawing, forming a part thereof.

Figure 1 is a front elevational view of a drink stirrer showing my new design;

Fig. 2 is a side elevational view of the stirrer, shown in Fig. 1;

Fig. 3 is a top view of the stirrer shown in Fig. 1;

Fig. 4 is a sectional view taken along line 4—4 of Fig. 2; and

Fig. 5 is a bottom view of the stirrer shown in Fig. 1.

I claim:

The ornamental design for a drink stirrer or similar article, substantially as shown.

ROBERT R. BORGFELDT.
